MASSAGING DEVICE

Lucy Cotton, Miami, Fla.

Application December 3, 1946, Serial No. 713,692

2 Claims. (Cl. 128—24.1)

1

This invention relates to neuro massagers and the like, and aims generally to improve the same.

In massaging to relieve bodily aches and pains incident to muscular soreness, neuritis, and other ailments, or for the purpose of developing muscles which have become debilitated as an aftermath of immobilization or long illness, finger manipulation of the muscles and tissues is particularly beneficial. Application of heat in such cases is also particularly efficacious, and to some degree the rubbing of the area with a concave body tends to produce a suction effect and promote circulation in the affected part.

As heretofore practiced these treating procedures have been separately applied. The heated or concave body sometimes employed as a massage tool has uniformly been formed to be grasped by the hand of the practitioner (or patient, in the case of self-treatment). Usually such body has been of wand-like formation, with an elongated handle to be grasped by the user. Sometimes such body has been handle-less, and of approximately the size of a flattened tennis ball. In such case the body has itself been grasped and rubbed against the area being treated.

This requirement that the instrument be grasped by the user has been a substantial handicap. This has been particularly true in treatments in which both finger and instrument manipulation are desirable. In such cases, during self-treatments where but one hand may be used, this factor has required laying aside of the instrument during finger manipulation, and cessation of finger manipulation during use of the implement. In treatments in which two hands may be employed, even when the practitioner is ambidexterous, it has required that but one hand be employed for each operation. And in the case of a strongly right handed or left handed practitioner, or in situations in which one hand must be employed to support the member being treated with the other, the lay-aside technique has interfered with continuity of treatment.

The present invention is particularly adapted to overcome these difficulties with prior massaging implements, and aims to provide an improved instrument, or masseur, which may be mounted in the palm of the hand in a manner providing for simultaneous finger and instrumental manipulation of the affected area.

To this end the invention has among its objects, severally and interdependently, the provision of an improved masseur, adapted to be secured in the palm of the practitioner and enabling the hand, or each hand of the practitioner,

when two instruments are used, to perform simultaneous finger and instrument manipulation of the area under treatment; the provision of a palm-cupped masseur attachable to the palm and requiring no grasping by the fingers, so that the fingers are left free for finger manipulation concurrent with use of the instrument; the provision in such an instrument of means for securing it in the palm without interfering with freedom of the hand for finger manipulation; the provision of advantageous means, preferably electrical, for heating the treating surface of such an instrument; and the provision in such a massaging device of means for controlling the conductor cord of the electrically energized masseur to prevent interference thereof with the massaging operation.

Further objects and advantages of the invention, as will appear from the following description of a preferred embodiment thereof, reside in the provision of particular features and combinations of parts, contributing to the realization of the aforesaid objects.

In the accompanying drawings of such preferred embodiment:

Figs. 1 and 2 are side elevation and bottom plan views of a device according to the invention, showing the securing thereof during use.

Fig. 3 is a detailed sectional view through the masseur.

Fig. 4 is a plan view of the heating and thermostatic elements.

Fig. 5 is a detailed view of the means for controlling the cord in the carpal region.

Fig. 6 is a similar view of a modified cord controlling means.

As is clearly shown in Figs. 1 and 2, the device of this invention generally comprises a palm-cupped treating member or masseur A, adapted to be secured in the hollow of the hand under the metacarpus so as to leave the phalanges or fingers free for digital manipulation. In the preferred form, the metacarpally received masseur A is disc-like and circular, and is provided with a securing device on mounting element B, which extends forwardly from one edge of the member A, thence upwardly between the fingers of the user, and thence rearwardly along the back of the hand between the bones of the metacarpus. The forward and rearward extensions of the mounting element B are of sufficient length to secure the device firmly in the hollow of the metacarpus, and the rearward extension is spaced from the top surface of disc A by a sufficient distance to comfortably embrace the metacarpus. As a general rule a length of about an inch for

2

the forward extension and about an inch and a half or so for the rearward extension, and a spacing of approximately an inch, will be found suitable, and it will be found that projection of the member B between the third and fourth phalanges in close proximity to the metacarpus is most advantageous.

In the preferred embodiment the metacarpal disc A is electrically heated, as hereinafter described, and the mounting means B is formed of hollow tubing through which extends the appliance cord C provided with a terminal plug D to supply current to the heating element.

The carpal portion of the cord C, adjacent the wrist of the user, is provided with a cord controlling means E, to prevent the cord from interfering with the massaging operation. In the form shown, this controlling means E comprises a slide member, through which the cord is loosely passed, this slide member being provided with a wristband F, hereinafter described, for securing it to the wrist of the practitioner.

As is well shown in Figs. 2 and 3, the metacarpal disc A is preferably circular and has a diameter and thickness adapting it to be snugly nested in the hollow of the palm. A diameter of about two inches is suitable, and a thickness of a quarter to a half-inch, more or less, may be employed. The disc A is suitably secured to the support 13, as by welding, soldering, threading and sweating, or otherwise. The cord C for long life, comfort and safety, is preferably asbestos insulated and rubber covered, or equivalent thereto, and the plug D is likewise preferably formed of or covered with soft, rubber-like material.

The disc A in the form shown has a convex top surface 10 (Fig. 3) and a concave under surface 11, and has smoothly rounded side edges 12. The disc A is thus adapted to fit comfortably in the metacarpal arch, to massage smoothly the area being treated, and to have a suction effect thereon which stimulates the circulation and tends to open the pores.

The disc A in this electrically heated form, is hollow and encloses a heating element 13. This element may be suitably heat insulated with respect to the portions of the disc A contacted by the hand of the practitioner, as by asbestos or other suitable heat insulating material 14. The heating element 13 may consist of resistance heating coils 15, which may be wound on a suitable frame of mica, asbestos, or other heat resistant insulating material, with terminals at 16. Where the heating coils are not otherwise insulated, as in the form shown, a thin asbestos sheet 17 may be interposed between them and the wall 11 (Fig. 3). In the preferred form, the lower wall portion 11 of the masseur A is spring-hinged to the upper portion 10 thereof, the joint being at the edge 12 in non-scratching relation to the area being treated, and being nicked at 18 to enable opening of the case, as by the fingernail, to give access to the heating element.

The heating element 13 is so designed as to raise the temperature of the bottom wall 11 of the masseur to the vicinity of 130° F. This degree of heat is not injurious, and has been found beneficial in treatments of the class concerned. In the preferred embodiment, a thermostatic element 19 is provided in the disc A and exposed in heat exchange relation to the bottom wall 11 to hold the temperature at the desired level.

The cord C, in the form shown, is soldered or otherwise connected to the heating coil terminals 16 (with the thermostat 19 interposed in one of the leads), and passes through the tube B, as shown.

At its carpal portion, which lies adjacent the wrist of the user, the cord C carries the supporting means E shown as comprising a ribbon-slide 20, mounted on the elastic band or ribbon F, and carrying a cord embracing member 21, shown as tubular and as having rounded flaring ends to avoid cord breakage, and through which cord C is freely slidable. The members 20 and 21 may be secured together in any suitable manner, as by welding, or the supporting means E may be made in other forms.

As shown in Fig. 5, the ribbon or elastic F is preferably provided with a tightener 22 and hook and loop members 23 and 24 so that it may be snugly fitted to the wrist. In this manner the carpal portion of the cord C is secured to the wrist, and prevented from interfering with the massaging operation. The supporting means E, F secured on the cord cannot become lost therefrom, as the plug D cannot pass through the member 21.

In the modification, Fig. 6, which shows another illustrative form of means for supporting the carpal portion of the cord C, the cord holder E' comprises a plaque 20a which may have smoothly rounded corners and edges and be curved to fit the wrist. This plaque 20a has suitably secured to it the flaring tubular cord embracing member 21a and means, shown as six pins 25 having enlarged heads, for securing the plaque to the wrist embracing means F', herein shown as made up of coil-spring strands 26, having loops at their ends secured to the pins 25 and to similar pins 27 which may be carried by a clasp device 23', 24' when such device is used. This arrangement is similar in operation and advantages to that of Fig. 5, and being of all metal construction, is easily kept clean and non-odorous. Its parts, like all the exposed metal parts of the device, present corrosion and tarnish resistant surfaces. To this end the various parts of the device may be formed of stainless steel, or may be plated with chromium or other suitable non-tarnishable metal.

From the foregoing description of a preferred embodiment of the invention, it will be apparent that the fundamental features thereof may be embodied in forms other than those selected to illustrate the same, and that the described embodiments are illustrative and not restrictive of the invention, the scope of which is pointed out in the appended claims.

I claim:

1. A massaging device comprising a masseur in the form of a disc sized to nest in the hollow of the hand under the metacarpal arch, said disc having a mounting element which, when the disc is nested in the metacarpal arch, extends from its forward edge parallel to the metacarpal bones, upward between the third and fourth phalanges, and rearwardly along the metacarpus, to hold the device in place while leaving the phalanges free for digital manipulation of an area being treated.

2. A massaging device comprising a masseur in the form of a disc sized to nest in the hollow of the hand under the metacarpal arch, said disc having a mounting element which, when the disc is nested in the metacarpal arch, extends

from its forward edge parallel to the metacarpal bones, upward between the third and fourth phalanges, and rearwardly along the metacarpus, an electrical heating element in said disc, and a conductor cord therefor extending through said mounting element and insulated therefrom.

LUCY COTTON.
